[57] CLAIM

The ornamental design for an agricultural sweep, substantially as shown and described.

DESCRIPTION

FIG. 1 is a plan view of the upper surface of an agricultural sweep showing our new design;

FIG. 2 is a side elevation view of the sweep;

FIG. 3 is a bottom plan view of the sweep;

FIG. 4 is a front elevation view of the sweep;

FIG. 5 is a rear elevation view of the sweep;

FIG. 6 is a perspective view of the upper surface of an agricultural sweep showing a second embodiment of our new design;

FIG. 7 is a side elevation view of the sweep shown in FIG. 6;

FIG. 8 is a front elevation view of the sweep shown in FIG. 6;

FIG. 9 is a plan view of the upper surface of the sweep shown in FIG. 6;

FIG. 10 is a rear elevation view of the sweep shown in FIG. 6; and

FIG. 11 is a perspective view of the lower surface of the sweep shown in FIG. 6.
